UNITED STATES PATENT OFFICE.

CHARLES F. McEWAN, OF OAK PARK, ILLINOIS, ASSIGNOR TO HARRY D. LATHROP, OF CHICAGO, ILLINOIS.

CAN-REVERSING MECHANISM.

Application filed December 24, 1918, Serial No. 268,121. Renewed November 22, 1922.

To all whom it may concern:

Be it known that I, CHARLES F. McEWAN, a citizen of the United States, and a resident of the city of Oak Park, county of Cook, 5 and State of Illinois, have invented certain new and useful Improvements in Can-Reversing Mechanism, of which the following is a specification.

My invention relates to improvements in 10 can reversing mechanism designed for use especially in connection with can washing machines, and has for its object the production of mechanism of this character which will be of durable and economical construction 15 and highly efficient in use.

A further object is the production of can reversing mechanism as mentioned, which will be adapted for use in connection with cans of various sizes. A still further object 20 is the production in can washing machinery of an improved arrangement for accommodating cans having covers permanently associated therewith.

Other objects will appear hereinafter.

25 The invention consists in the combinations and arrangements of parts hereinafter described and claimed.

The invention will be best understood by 30 reference to the accompanying drawings forming a part of this specification, and in which,

Fig. 1, is a side elevation of a can washing machine embodying the invention, a portion of the housing thereof being broken 35 away to expose underlying parts,

Fig. 2, a partially sectional top plan view of the discharge end of the machine,

Fig. 3, an enlarged section taken on substantially line 3—3 of Fig. 1,

40 Fig. 4, a side elevation of the discharge end of the can washing machine proper, the can discharge passage or chute being omitted,

Fig. 5, a view similar to Fig. 3, showing 45 the method of toppling the can, and

Figs. 6 and 7, enlarged sections taken on lines 6—6 and 7—7, respectively, of Fig. 1.

The preferred form of construction, as 50 illustrated in the drawings, comprises an elongated framework 10, in which is arranged a can guide which is constituted by two elongated spaced parallel bars 11—11, as clearly seen in Figs. 2, 6 and 7. Arranged adjacent to and parallel with the can guide

is a cover guide, constituted by two spaced 55 parallel bars 12, as clearly seen in the same figures above referred to. The arrangement is such that the can and cover guides are adapted to accommodate a can A and its cover B, with the can in inverted position, 60 as clearly seen in Figs. 3, 5 and 6. The cover is permanently associated with the can, being connected thereto by a link C, and, in order to accommodate said link in the passage of the can and cover through 65 the machine during the washing or cleansing operation, an elongated open space 13 is provided intermediate the can and cover guides, as clearly seen in Figs. 3 and 6.

The feeding or advance of the can 70 through the machine is accomplished through the medium of a plurality of spaced pairs of tiltably mounted pawls 14 which are carried by reciprocating bars 15 arranged between the guide rails 11, the bars 15 being operatively connected with a manually operable lever 16 fulcrumed at 17 at the entrance end of the machine. The arrangement is such that, through tilting of lever 16, the pawls 14 will be reciprocated, 75 causing intermittent advance of a can mounted upon the can guide. In this advance of the can, its cover will of course be correspondingly moved, inasmuch as the same is permanently associated therewith 80 through the medium of the connecting link C. The cleaning or washing of the can and cover takes place during this intermittent travel, as will be readily understood by 85 those skilled in the art.

In order to hold the covers down in operative relation with the cover guide during the advance of the same through the machine, an elongated resilient plate or strap 18 is provided, which is adapted to bear 90 against the tops of the covers, as clearly seen in Figs. 1 and 6. A bar 19 is provided along the side of the cover guide adjacent the can guide, against which the covers are adapted to abut, said bar serving to hold 100 the same against lateral displacement from the cover guide, as might otherwise result in the advance of the can to which the cover is attached.

Arranged at the discharge end of the can 105 guide is a horizontally positioned platform 20, secured to a supporting bar 21, which is rockingly mounted in bearings 22 and 23,

as clearly seen in Fig. 2. Carried by the platform 20 is a laterally projecting extension 24, which is positioned for registration with the cover guide, the arrangement being such that, with said platform in horizontal position, upon the pushing of a can from the can guide, the can will be positioned upon said platform, whereas the cover thereof will be positioned upon the 10 platform extension 24.

The bar 21 is formed with a laterally projecting arm or crank 25, which engages against a strap 26, carried by a reciprocating bar 27 having operative connection 15 with the operating lever 16. The arrangement is such that, when the bar 27 is at its rearward terminal of movement, the arm 25 will engage with the straight elevated portion of the strap 26, as seen in Fig. 3, and 20 thereby serve to hold the platform 20 in horizontal position, or in the position seen in Fig. 3. Upon forward movement of the bar 27, the arm 25 will be brought into registration with a recess 28 formed in the strap 25 26, which recess will permit of the downward swinging of said arm and hence of corresponding tilting of the platform to the position seen in Fig. 5. This tilting of the 30 platform is sufficient to effect the toppling 35 of a milk can which may be positioned thereon, so that the can will fall laterally toward the left, as seen in Fig. 5.

Provided to the left of said platform is a stationary transversely curved bumper or 35 stop 29, against which the can, when toppled, is adapted to fall, after which the can, by gravity, is caused to completely reverse so as to alight on an adjacently positioned platform 30 in an upright position, as 40 seen in dotted lines in Fig. 5. A rail 31 provided around the platform 30, prevents the can from sliding or being thrown beyond said platform, said rail positively insuring the centering of a can on said 45 platform after toppling of the same, through the medium of the platform 20.

Leading from the platform 30 is an inclined discharge chute 32 down which the can is adapted to be thrust by a pivoted arm 50 33, which is fulcrumed at 34, one end thereof engaging with a slot 35 provided in the reciprocating bar 27.

With the construction set forth it will be seen that in the operation of the machine, 55 the cans will be intermittently advanced through the machine through actuations of lever 16. As each can, with its cover, has passed through the cleansing operation, the same will be fed to position on the platform 60 20, the cover assuming a position upon the platform extension 24. After the can has reached this position, upon the next forward movement of the bar 27, bringing the recess 28 of strap 26 into registration with 65 the arm 25, platform 20 will be released for

tilting. Said platform is unevenly balanced, that is, the axis thereof is positioned to one side of the center of the platform or to the right, as seen in Fig. 2, so that immediately upon being released as mentioned, 70 the same will tilt of its own accord, such tilting being also aided by the weight of the can, which will be positioned on the platform at one side of the axis thereof. Thus, immediately upon the release of the 75 platform, the can will be toppled into engagement with the stop 29, whence the same, by gravity, will be caused to completely reverse, finally alighting on the platform 30 in fully righted position, after which the 80 same will be automatically pushed down the discharge chute 30 by the arm 33. In the toppling of the can, the cover thereof, of course, is carried along with the same, and by reason of the direction of toppling of the 85 can relative to the position of the connecting link between the can and the cover, the latter will be automatically carried to closed position over the top of the can, as seen in Fig. 5. Upon rearward movement of the 90 bar 27, the arm 25 will again be brought into engagement with the elevated portion of the strap 26, causing said arm to be rocked upwardly, and hence the platform 20 to be returned to horizontal position in order to accommodate the succeeding can.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope 105 of the appended claims.

Having described my invention, what I claim as new and desire to secure by Letters Patent is:—

1. A can reversing mechanism comprising 110 a tiltable platform adapted to receive a can; means for tilting said platform and when tilted to topple the can; and a bumper against which only the central portion of the can is adapted to engage when the can 115 is toppled, whereby said can, by gravity, is caused to be reversed completely, substantially as described.

2. A can reversing mechanism comprising 120 a tiltable platform adapted to receive a can; means for tilting said platform to topple said can; and means against which only the central portion of the can is adapted to fall when toppled, whereby said can, by gravity, is caused to be reversed completely, 125 substantially as described.

3. A can reversing mechanism comprising 130 a tiltable platform adapted to receive a can; an extended platform supported by said tiltable platform adapted to receive a cover,

- 12 said cover being permanently connected to said can; means for tilting said platform to topple said can; and stationary means against which only the central portion of 5 the can is adapted to fall when toppled, whereby said can, by gravity, is caused to be reversed completely, substantially as described.
- 13 4. A can reversing mechanism comprising 10 a tiltable platform adapted to receive a can; an extended platform supported by said tiltable platform adapted to receive a cover, said cover being permanently connected to said can; means for tilting said platform 15 to topple said can, whereby said can, by gravity, is caused to be reversed completely; and a chute adapted to receive said can when reversed, substantially as described.
- 14 5. Can reversing mechanism comprising a 20 tiltable platform engageable with only the base portion of the can, adapted to topple the can; and means against which only the central portion of the can is adapted to fall when toppled, whereby said can, by gravity, 25 is caused to be reversed completely, substantially as described.
- 15 6. Can reversing mechanism comprising a 20 tiltable platform adapted to receive a can, and, when tilted, to topple the can; and stationary means against which only the central portion of the can is adapted to fall when toppled, whereby the can, by gravity, 30 is caused to be reversed completely, substantially as described.
- 16 7. Can reversing mechanism comprising a 25 tiltable platform adapted to receive a can, and, when tilted, to topple the can; means against which only the central portion of the can is adapted to fall when toppled, 40 whereby the can, by gravity, is caused to be completely reversed; means for normally holding said platform in horizontal position; and means for tilting said platform when released, substantially as described.
- 17 8. Can reversing mechanism comprising a 45 tiltable platform adapted to receive a can, and, when tilted, to topple the can; means against which only the central portion of the can is adapted to engage when the can 50 is toppled, whereby the can, by gravity, is caused to be reversed completely; and means for normally holding said platform in horizontal position, said platform being unevenly balanced, whereby the same automatically tilts when released, substantially as described.
- 18 9. A can washing machine comprising a 55 can guide; a parallel adjacently positioned cover guide, there being an open space between said can and cover guides for the 60 passage of a connecting link between the can and cover; and can reversing mechanism comprising a platform onto which a can and cover may be moved, said platform, upon tilting, being adapted to topple the 65 can, substantially as described.
- 19 10. A can washing machine comprising a 70 can guide; a parallel adjacently positioned cover guide, there being an open space between said can and cover guides for the 75 passage of a connecting link between the can and cover; can reversing mechanism comprising tiltable means onto which a can and cover may be moved, said means, upon tilting, being adapted to topple the can; and means against which the can is adapted to fall when toppled, whereby the can, by gravity, is caused to be reversed completely, substantially as described.
- 20 11. A can reversing mechanism comprising 80 a tiltable platform adapted to receive a can; an extended platform supported by said tiltable platform adapted to receive a cover, said cover being permanently connected to said can; means for tilting said 85 platform to topple said can, whereby said can, by gravity, is caused to be reversed completely; a chute adapted to receive said can when reversed; and means for automatically pushing said can down said chute, 90 substantially as described.
- 21 12. A can reversing mechanism comprising 95 a rocker arm; a tiltable platform supported by said arm adapted to receive a can; a reciprocating strap having a downwardly projecting recess slidably engaging said arm for tilting said platform to topple said can; a bumper against which only the central portion of the can is adapted to engage when the can is toppled, whereby said 100 can, by gravity, is reversed completely; a chute arranged to receive said can when reversed; and means for automatically pushing said can down said chute, substantially as described.

105 In testimony whereof I have signed my name to this specification in the presence of two subscribing witnesses.
